UNITED STATES PATENT OFFICE

1,933,417

APPARATUS FOR WETTING SKIP CAR CHARGES

Hugh B. Conover, Steubenville, Ohio, assignor to Carnegie Steel Company, a corporation of New Jersey

Application August 28, 1931. Serial No. 560,037

2 Claims. (Cl. 266—27)

This invention relates to a method and apparatus for wetting blast furnace charges carried by skip cars, one of the objects being to accomplish the above in a speedy and accurate manner. 5 It is to be understood that blast furnace charges must ordinarily first be wetted down before being loaded into the furnace, this being done to prevent the creation of dust in the furnace which might lead to undesirable results. Further, it 10 is necessary that just the right amount of fluid be added to the charge for; if too small, the charge will not be properly wetted and, if too large, the moisture content of the furnace gases will rise to an undesirable extent.

15 In the drawing:

The figure illustrates one example of the apparatus incorporated in this invention and the method of its use.

Having reference to this drawing, there is 20 shown a steeply inclined track 2 carrying a skip car 3 whose movements are controlled by a cable 4. This skip car carries a charge for loading into a blast furnace, which must first be wetted down. This is accomplished according to this invention 25 by having a fluid under pressure conduit 5 positioned to discharge fluid into the skip car 3, this conduit 5 being connected through a valve 6 to a main fluid supply line 7.

The valve 6 is connected by a system of links 30 and/or levers 8 to a solenoid 9. The system of links and/or levers 8 includes a counterweight 8^a which acts to normally bias the valve 6 to closed position. This solenoid is energized by the power line 10 through the adjustable time limit relay 35 apparatus 12, having a manually operable starting button 13.

All of these parts are standard equipment ordinarily supplied by manufacturers of electrical apparatus. In use, the skip car is positioned as 40 shown and the button 13 is pressed to energize the solenoid 9 so that the valve 6 is opened and fluid begins to flow through the conduit 5 under pressure from the supply line 7. The time limit relay apparatus 12 has previously been set so that 45 after a thus predetermined interval of time the solenoid 9 will automatically be deenergized so that the valve 6 will be closed. By this means a predetermined flow of fluid may be discharged into the skip car 3 so as to wet the charge carried 50 thereby almost as quickly as the cars can be positioned thereunder. This is a great improvement over the methods and apparatus heretofore used, which consisted mainly in the use of an elevated tank arranged to discharge into the skip 55 car, it being necessary for a workman to manu-

ally operate a valve to fill the tank, from which it was then allowed to slowly drain into the skip car. The use of this latter apparatus and method results in much delay and frequently in inaccurate results caused by the fact that the workman 60 may not completely fill the tank.

Although a specific form of this invention has been shown in accordance with the patent statutes it is not intended to limit the scope of this invention exactly thereto, except as is defined in 65 the appended claims.

I claim:

1. In combination with a skip car carrying a blast furnace charge, means for discharging fluid into said skip car comprising a fluid conduit, a 70 valve for controlling the fluid supply to said conduit, an operating link for said valve, a pivoted lever connected to said link, a counterweight for biasing said pivoted lever, a solenoid constructed and arranged to move said pivoted lever against 75 the biasing influence of said counterweight, an adjustable time limit relay apparatus for controlling said solenoid and manually operable means for initiating the operation of said time limit relay apparatus. 80

2. In combination with a skip car carrying a blast furnace charge, means for discharging fluid into said skip car comprising a fluid conduit, a valve for controlling the fluid supply to said conduit, an operating link for said valve, a pivoted 85 lever connected to said link, a counterweight for biasing said pivoted lever in such manner as to close said valve, a solenoid constructed and arranged to move said pivoted lever against the biasing influence of said counterweight, an ad- 90 justable time limit relay apparatus for controlling said solenoid and manually operable means for initiating the operation of said time limit relay apparatus.
